UNITED STATES PATENT OFFICE.

EDGAR O. MARTY, OF POTTSVILLE, PENNSYLVANIA.

GRAVITY SEPARATOR AND PROCESS OF SEPARATION.

Application filed July 24, 1924, Serial No. 727,924. Renewed January 10, 1927.

This invention relates to gravity separators and particularly relates to apparatus for separating slate, rock and other incombustible matter from coal, or for separating 5 the heavier metals from rock and the like.

The present disclosure may be regarded as an improvement upon the structure disclosed by my pending application, Serial No. 707,546, filed April 19, 1924.

10 Heretofore the separation of materials and more particularly the separation of coal from incombustible substances has been accomplished by continuously discharging the mixture containing coal into the upper end 15 of a hopper, while maintaining an upward current of water through said hopper, the velocity of flow being such as to float the coal in the upper portion of the container while permitting the slate, rock and like relatively heavier substances to settle in said 20 hopper.

In the pending application above identified, there is disclosed a provision for independently regulating the velocity of the upward flow of water and the volume of such flow to better adapt such an apparatus to handle materials of different characteristics.

In making such provision, the disclosure disposes within a hopper or the like, a substantially central hollow head, adjustable to 30 vary the annular passage around said head.

The present invention has for one of its objects the use of such a head as a pressure chamber, and the utilization of an upward 35 discharge of liquid from said chamber to separate a mixture of materials according to their specific gravities.

A further object of the invention is to subject a mixture of materials successively to 40 upward liquid currents to accomplish a preliminary and a final separation of the materials according to their specific gravities.

A still further object is to provide an improved means for agitating a mixture of materials preliminary to or during hydraulic separation thereof according to their specific gravities.

These and various other objects are attained by the construction hereinafter described and illustrated in the accompanying drawings wherein,

Figure 1 is a sectional elevation of the improved apparatus, in one embodiment thereof.

Figure 2 is a plan view of the same.

Figure 3 is an enlargement of a portion of Figure 1 primarily disclosing the features adapting the aforementioned hollow head to discharge an upward current of 60 liquid.

In these views the reference character 1 designates a funnel shaped hopper supported at a suitable elevation upon a frame 2. A pipe 3 controlled by a valve 4 is adapted to deliver water or another suitable liquid upwardly through said hopper, the bottom of the latter preferably having an upward extension 5 with a conically flared upper end 6 forming an outlet for said pipe.

Substantially centrally within the hopper 1, a hollow head 7 is arranged so as to form an annular passage 7^a for the upward flow of water delivered by the pipe 3. Said head has reversely coned upper and lower portions, the upper of which is formed with an internal central sleeve 7^b, with which is rigidly engaged the lower end portion of a vertical pipe or hollow shaft 8, functioning both as a support for the head 7 and as a liquid supply connection thereto. Said pipe engages a pair of slide bearings 9 suitably mounted upon the frame 2 and above the latter a hose 10 or other flexible conduit has a supply connection to said pipe.

The hollow head 7 has formed in its top portion an annular slot 11 and said portion is reinforced by a plurality of internal radial ribs 12, rigidly holding together the portions of said head above and below said slot. 90 13 designates a sheet metal cover plate for the slot 11, formed preferably of brass or bronze or some other non-rusting metal, and uniformly perforated throughout its area as indicated at 14 to provide for an upward discharge of liquid from the head 1 throughout the annulus formed by the slot 11.

In its bottom portion, the head 7 is formed with a clean-out opening 15 normally closed by a plug 15^a.

The impure coal or other mixture requiring separation is delivered by a chute 15^b to a cylindrical distributing chamber 16 arranged above the head 1 and mounted fast upon the pipe 8 in a coaxial relation thereto by a spider 17. Preferably the chamber 16 has its lower portion 18 vertically adjustable to vary the space between said portion and the head 1 through which material discharges from said chamber upon the coned top face 110 of said head. Thus, inclined slots 19 may be formed at suitable points in the lower

end portion of the main body of the chamber 16, through which extend clamping bolts 20 carried by the adjustable part 18 of said chamber. Thus, rotation of the part 18 will shift the bolts 20 toward the upper and lower ends of the slots 19 and will thereby raise or lower said part 18. Said bolts will further clamp the part 18 in adjustment.

Describing now the means for supporting the pipe 8 and head 7 and for vertically adjusting the same, 21 designates a threaded portion of said pipe arranged between the slide bearings 9, and 22 is an adjusting collar engaging said portion and seating upon a plate 23 horizontally carried by the frame 2. When said collar is rotated by any suitable means, the pipe 8 and head 7 are raised or lowered according to the direction of actuation of said collar.

Upon the body portion of the chamber 16 there is rigidly exteriorly mounted a ring 24 rotatively seating an annular worm gear 25 adapted to be gradually driven by a worm 26 actuatable by a pulley 27. 28 designates a plurality of agitator or spreader bars, rigidly carried by and depending from the gear 25 around the chamber 16. Preferably the lower end portions of said bars closely approach the head 7 adjacent the mixture outlet from the chamber 16, and preferably said rods are secured to the gear 25 by bolts 29 vertically mounted in said gear and having split portions below the latter wherein the bars 28 are clamped as indicated at 30.

31 designates a frustro-conical separating ring arranged coaxially of the head 7 and upwardly spaced from said head, preferably slightly below the central horizontal plane of the slot 11. Said ring is carried by a plurality of hanger rods 32 having their upper ends engaging a spider ring 32^a mounted fast upon the chamber 16. The separator ring 31 and its supporting rods 32 are adapted to be adjusted vertically by threading the upper ends of said rods and engaging therewith nuts 35 seating upon the ring 32^a. While the provision for disposal of the heavier substances which are separated out by the described apparatus is not a feature of the present invention, it may be said that such materials discharge from the hopper 1 through an inclined passage 36 into a tank 37 from which they are continuously elevated by a bucket conveyer 38, discharging from the latter to a chute 39.

In the operation of the described invention, a mixture containing coal (or some other material to be separated out) is continuously delivered through the chute 15^b to the distributing chamber 16, discharging from the latter upon the conical top face of the head 7. Flowing down the incline of said head, the mixture encounters the upward current of liquid discharging through the perforations 14. The pressure of liquid

produced within the head 7 is so regulated as to impart to the discharge through said perforations a velocity adequate to raise any coal flowing across the perforated plate a distance above the head 7 exceeding that at which that ring 31 is spaced from said head. Such heavier impurities as may be mixed with the coal will remain adjacent the head 7 and will flow down the incline thereof beneath the said ring. These impurities upon reaching the point of maximum diameter of said head will descend through the annular passage 7^a surrounding the lower portion of the head, whence they will be conducted through the passage 36 into the tank 37.

The coal elevated by the discharge through the perforations 14 will contain only a small proportion of the heavier impurities, if any. A portion of this coal may rise directly to the liquid level indicated at 40 but the larger portion will slide down the inclined surface of the ring 31 until it encounters the current of liquid rising between the head 7 and hopper 1. The velocity of this current will be adequate to carry the coal upwardly, adjacent the hopper wall, to the overflow point at the upper edge of said wall, where the coal together with the overflowing liquid will discharge into an annular trough 41 surrounding the upper portion of the hopper, whence it will continuously discharge by way of a chute 42. Any residue of the heavier impurities still remaining in the coal after its passage above the separator ring 31 will drop out and descend through the annular passage 7^a when the coal is being elevated by the current discharged from said passage. Said current is regulated as to volume by the valve 4 and as to velocity by adjustment of the head 7 vertically through turning the collar 22.

By properly regulating the velocity and volume of the current, the coal may be floated to the overflow point with a minimum expenditure of power to produce such flotation.

It is to be noted that in the preliminary (and primary) separation which is accomplished by the upward discharge from the head 7 the material being treated, is spread out in a thin layer upon the top surface of said head so that the current rising through this layer may act most effectively upon the same. Further it will be seen that this current is required to elevate the coal only the slight distance necessary to allow the heavier impurities to pass below the separator ring 31, while the coal passes therabove. Thus the pressure of liquid necessary to accomplish the preliminary separation is minimized.

By preliminary removal from the coal of the major portion of its heavier impurities and leaving only a small portion (if any) of impurities to be removed during eleva-

tion of the coal by the current rising adjacent the wall of the hopper 1, it is practically assured that this final separation will be quite thorough. As the coal is being 5 raised finally to the overflow point, the quantity of descending heavier impurities is so slight as to offer very little resistance to upward travel of the coal.

It is desirable to locate the slot 11 some 10 distance from the lower edge of the head 7 so as to avoid interference between the current flowing through said slot and that rising around said head. Use of the ring 31 permits such a location of the slot while 15 preventing the stratum of coal which is elevated in passing over the slot, from again settling down among the heavier impurities before the current rising around the head is encountered.

20 By adjusting the nuts 35 upon the upper ends of the rods 32, the separator ring 31 may be spaced above the head 7 in its most effective position.

While the invention has been described 25 as embodied in a machine generally known as a coal washer, it is to be understood that the disclosed principles of construction and operation are applicable to the grading and separating of any mixture of materials differing as to their specific gravities.

It will be noted that a portion of the hopper 1 adjacent to its upper margin is inclined reversely to the body of said hopper, thus somewhat restricting the hopper 35 outlet and consequently increasing the depth of overflow above the outlet edge. Thus there is assured a sufficient depth above said edge to permit carrying over the latter of the larger particles of coal.

40 What I claim is:

1. A gravity separator comprising a hopper, means for producing an upward current of liquid within said hopper, a hollow head within said hopper forming an annular passage for said current, said head having an upward discharge opening, means for delivering a mixture of materials differing as to specific gravity upon the central portion of said head, the top of said head being 45 inclined to deflect said materials toward said annular passage, a pipe supporting said head and means for delivering a fluid through said pipe to the head for discharge through said opening to effect a flotation of a lighter one of said materials preliminary 55 to a separation effected by the current through said annular passage.

2. A gravity separator comprising a hopper, means for delivering a mixture of materials differing as to specific gravities to the central upper portion of said hopper, a hollow head substantially co-axial with and spaced from said hopper having a conical upper face and forming with the hopper 60 wall an annular passage, and having a dis-

charge opening in said face below the discharge point of the materials upon said head, means for delivering a fluid under pressure to said head to discharge upwardly through said opening, a ring spaced above 70 a portion of said surface below said opening for separating one of said materials elevated by the discharge from said opening, and means for producing an upward current of liquid through said annular passage, said 75 ring being adapted to deliver the heavier and lighter materials in vertically spaced relation to the upflowing current.

3. In a gravity separator, an inclined surface having a discharge opening therein, 80 means for delivering a mixture of materials differing as to specific gravities upon said surface above the level of said opening, whereby said materials are caused to descend upon said surface across said opening, means for effecting a fluid discharge upwardly through said opening, a member spaced above the portion of said surface below the level of said opening for effecting a preliminary separation from said mixture 85 of one of said materials elevated by said discharge, and means for producing an upward fluid current past the lower edge of said surface to complete said separation, said separating member being adapted to deliver 90 the preliminarily separated components to the upflowing current, the lighter above the delivery level of the heavier.

4. A gravity separator comprising a hopper, means for producing an upward current of liquid in said hopper, a hollow head within said hopper above said means, forming with the hopper an annular upward channel for the said current, said head having a substantially conical top portion 100 formed with a discharge opening below the overflow level of the hopper and adapted to deliver a fluid into the hopper, a pipe supporting said head and communicating therewith, means for supplying a fluid to said 105 pipe for delivery through said head to said discharge opening, means for vertically adjusting said pipe and head, and means for discharging a mixture of materials differing in specific gravities upon the central 110 portion of said head.

5. A gravity separator comprising a hopper, means for producing an upward flow of liquid within said hopper, means for delivering a mixture of materials differing as 115 to their specific gravities to the upper portion of said hopper, a member within said hopper forming an annular passage for the upflow of said liquid and for the downflow of the heavier of said materials, means for subjecting said materials within said hopper to an upward flow of fluid to effect a separation of the lighter materials preliminary to the separation effected by the current rising through said annular passage, and means for 125 130

regulating the upward flow through said annular passage independently of the fluid current effecting preliminary separation.

6. A method of separating a mixture of materials differing as to their specific gravities consisting in flowing said materials upon a perforated surface, maintaining an upward discharge of fluid through the perforations of said surface and through the flowing materials and thereby forming an overlying stratum of the lighter materials and an underlying stratum of the heavier materials, discharging the materials thus stratified from an edge of said surface, and in maintaining adjacent to said edge a relatively strong upflow of fluid adequate to elevate the upper stratum to a higher level while permitting descent of the heavier stratum.

7. The method of separating a mixture of materials differing as to their specific gravities, consisting in flowing said materials upon a perforated surface, maintaining an upward discharge of fluid through the perforations of said surface and through the flowing materials, regulating the velocity of such discharge to form an overlying stratum of the lighter materials and an underlying stratum of the heavier materials, discharging the materials thus stratified from an edge of said surface, maintaining a relatively strong upflow of fluid adjacent to said edge, and in regulating the last mentioned upflow independently of the discharge through said surface to elevate the upper stratum of materials to a higher level while permitting descent of the lower stratum.

8. The method of separating a mixture of materials differing as to their specific gravities, consisting in flowing such materials down an inclined surface upon all sides of said surface maintaining an upward discharge of fluid through said surface and

through the downflowing materials, thereby forming an overlying stratum of the lighter materials and an underlying stratum of the heavier materials, discharging the materials thus stratified from said surface at the lower edge of its inclination, and in maintaining a relatively strong upflow of fluid surrounding said surface adequate to elevate the overlying stratum while permitting descent of the underlying stratum.

9. In a gravity separator, a separating chamber, means for delivering into the upper portion of said chamber a mixture of materials differing as to specific gravity, means for discharging a fluid upwardly within said chamber, a member within said chamber above said discharge means vertically adjustable to control the fluid velocity, a spreader for said materials arranged above said control member, and adjustable vertically in unison with said control member, and means for rotatively actuating said spreader.

10. In a gravity separator, a separating chamber having a conical wall, means for delivering into the upper portion of said chamber a mixture of materials differing as to specific gravity, means for discharging a fluid upwardly within said chamber, a control member for the flow of said fluid arranged within said chamber above said discharge means, and forming with the conical wall of said chamber an annular passage for said flow, a vertical shaft carrying said control member, means for vertically adjusting said shaft to exercise the controlling function of said control member, and a spreader for the materials to be separated arranged above said control member and rotatable upon said shaft.

In testimony whereof I sign this specification.

EDGAR O. MARTY.
